GEORGE B. DURKEE AND WILLIAM H. MURRAY, OF CHICAGO, ILLINOIS, ASSIGNORS TO THEMSELVES AND ISAAC T. SAFFORD, OF SAME PLACE.

Letters Patent No. 71,862, dated December 10, 1867.

IMPROVEMENT IN PLANING-MACHINES FOR WOOD.

The Schedule referred to in these Letters Patent and making part of the same.

TO ALL WHOM IT MAY CONCERN:

Be it known that we, GEORGE B. DURKEE and WILLIAM H. MURRAY, both of the city of Chicago, in the county of Cook, and State of Illinois, have invented certain new and useful Improvements in Planing and Wood-Moulding Machines; and we do declare that the following is a full, clear, and exact description of the construction and operation of the same, reference being had to the annexed drawings, making a part of this specification, in which—

Figure 1 is a side view.

Figure 2, an end view.

Figure 3, a sectional view on red lines A' B' of fig. 2.

Figure 4, a front view, showing the cutter-heads in different planes; and

Figure 5 a cross-section of moulding finished by the machine.

Like letters refer to the same parts in all of the figures.

The nature and object of our invention consist in providing a planing-machine with two cutter-heads, so that one will follow the other and give the wood a fine finish, and so that for wood mouldings they can be set at different lines, planes, or angles, and plane boards beveling with straight-edged knives, and, with properly-formed knives, form mouldings with beads turned under and grooves cut under the body of the wood, so as to produce a variety with the same knives; in constructing the machine so that the plane or axis of rotation can be changed in both or either of the cutter-heads; in constructing the machine so that the line of cutting of either or both can be changed from one side of the machine to the other, or adjusted so that one will cut exactly on the same part of the wood as the other; in improving the cutter-head by making it of a single piece, and providing it with grooves or slots, so that the nuts which hold the knife-bolts can be placed in the cutter-head instead of on the outside, as heretofore has been done.

To enable others skilled in the art to make and use our invention, we proceed to describe its construction and operation.

A is the frame on which the machine is fastened, and is to be made of any suitable material and form. B are standards firmly attached to the frame, and slightly inclined to the rear. At the top of the standards B are inserted screws D, which pass through the heads of the standards and screw through connecting-bars e, which pass through the slots a laterally, and also through lateral slots i in the arm of the cross-head C. This connecting-bar e has a head on one end and a nut on the other end. By means of this nut the brass head C, when properly adjusted, can be held firmly in its place. By these screws D the incline of the cutter-heads is adjusted, and either end can be raised or lowered without changing the axis of rotation, and the axis of rotation can be adjusted separately in each cutter-head and at any desired angle, so that we are enabled to cut under the vertical line by a rotary cutter, as shown in fig. 5. At the side opposite to the pulley-wheels is a side arm, f, projecting from the arm of the cross-bar C, to the outer end of which is attached a head through which the screw G passes. Back of this arm is another arm, g, fitting into a slot made in the arm C, and having a lug attached to it fitting the slot a, so that it will slide up and down with C. The screw G is attached to the arm or bar g by a head on the end of the screw, or by a swivel-joint. By this means the lateral cut of the cutter-heads is adjusted, so that one can be made to cut directly in front or rear of the other, or changed so as to cut in different places.

We make our cutter-heads E, with their journals, of a single piece of steel, so that there is no getting out of order, slipping, or yielding. They revolve in boxes, the lower half of which we cast with and upon the arms of the cross-head C. The upper half of the boxes is detachable, and is held in place and adjusted by the screws b passing through the projection e. By removing the upper half of the box the cutter-heads can be removed and changed at pleasure. The cutter-heads are square, and are provided on each side with a T-shaped groove or cavity, provided with the additional groove or slot k, as shown in fig. 3. We place the nuts of the knife-bolts in this T-shaped groove instead of externally, as has been heretofore done; and the advantages of this arrangement are that we can use a larger nut in the groove, so that the bearing is always secure; and, as

the bolt-heads are outside, we can make them thin, and are thereby enabled to use a smaller cutter-head and shorter or narrower knives, so that there is less strain on the bolts. The groove or slot *k* admits of the passage of the bolts entirely through the nuts, so that their full strength can be obtained without any nice adjustments in the length of the bolts.

Four knives or cutters can be used on each cutter-head; but for mouldings where a rapid feed is not essential, one to each head will be found sufficient. The form of the knives must be adapted to the style of moulding desired; and by the use of two cutter-heads a much greater variety can be produced with angles cut under, and with deeper grooves, as one knife can be made to do a portion of the cutting, which will be finished by the one which follows; so that deep and fine grooves can be made without long points on the cutters, which are difficult to keep in order and liable to break. Great advantage will also be found in ordinary planing, as, by taking off the rough and gritty or dirty portions, and reducing the boards to an even thickness by the first cutter, it can be followed by the second with a high motion and very sharp knives, which will give the boards a perfect finish and polish; and with mouldings, and in planing siding, a bevelled edge can be given.

Having thus fully described our machine, what we claim as new and as our invention, and desire to secure by Letters Patent, is—

1. The employment of two separately adjustable cutter-heads in a single machine, so that the axis of one cutter may be at one angle and the other at a different angle, and both cutters operating at the same time upon the same board, substantially as specified.

2. The cross-heads C, cutter-heads E, screws D and G, in combination with the standards B, constructed and operating substantially as specified.

WM. H. MURRAY,
GEORGE B. DURKEE.
